[57] CLAIM

I claim the ornamental design for a minature roof gutter, as shown and described.

DESCRIPTION

FIG. 1 is a perspective view of the roof gutter embodying my new design;

FIG. 2 is an enlarged right-side elevational view, the left-side elevational view being a mirror image thereof;

FIG. 3 is a front elevational view thereof on a reduced scale;

FIG. 4 is a rear elevational view thereof on a reduced scale;

FIG. 5 is an enlarged bottom plan view thereof; and,

FIG. 6 is an enlarged top plan view thereof.

FIGS. 1, 3, 4, 5 and 6 are shown broken away in the middle to indicate indeterminate length.
